UNITED STATES PATENT OFFICE

THOMAS COTTER, OF EVANSVILLE, INDIANA

RELEASING THREADING DIE

Application filed March 1, 1929. Serial No. 343,794.

In the use of the ordinary threading die, when the thread has been cut on the rod, bolt, or the like, it is necessary to continue to reverse the direction of turning of the die stock until the die has completely backed off of the screw thread which it has previously formed, which requires time.

The object of my invention is to provide an improved threading die stock wherein the die will automatically tilt and expand when released, thus freeing itself from the screw threads which have been cut, enabling the die stock to be quickly removed.

A further object is to provide an automatically releasing threading die which can be quickly restored to normal threading condition after it has released from the screw thread which has been cut.

The foregoing objects are accomplished by the provision of an expandable screw threading die, an improved stock, and improved means on the stock whereby the die may be contracted and held in screw threading condition, or, allowed to tilt and to expand to free itself from the screw thread which has been cut.

While the invention is not to be considered as limited to the specific embodiment herein-after described and which is shown in the accompanying drawings, a practical embodiment is the one shown and described wherein one of the sections of the die is spring-expanded in relation to the other section thereof, the entire die and its holder or plates are contained within an improved stock in which the die and its plates may tilt from a normal contracted condition to an abnormal expanded condition, and a combined camming and locking device for contracting the die and forcing it into contracted, screw-threading, position and retaining it in that position, is provided.

In the accompanying drawings:

Figure 1, is a front view of the die and stock in threading condition;

Fig. 2, is a cross section showing the die in threading condition and illustrating a threaded bolt;

Fig. 3, is a similar view showing the die in tilted position, freed from the threaded bolt;

Fig. 4, is an edge view of the die and its plates, removed from the stock;

Fig. 5, is a front view thereof;

Fig. 6, is an edge view of one of the rings;

Fig. 7, is a front view thereof; and

Fig. 8, is an internal view of the die, the ring being removed to show the expanding springs.

The die stock is shown, generally, at 1, being provided with the usual handles by 60 which it may be turned. The stock has a die receiving cavity 2 which differs from the usual construction in that it is of greater width than the thickness of the die and the plates for the die so that the die and its plates 65 may tilt from the normal position shown in Fig. 2 to the abnormal position shown in Fig. 3. There is a supplemental chamber 2' in the die holder or stock which permits tilting of the die when desired, thus enabling 70 the die to automatically expand.

One or both walls of the chamber 2 may be removable but in the present instance one wall 3 is integral with the die stock, the other wall comprising a removable ring 4 secured 75 by screws 5 and having a lug or pin 6 projecting into the cavity 2 at a point diametrically opposite to the supplemental chamber or cavity 2', the purpose of the lug or pin 6 being to serve as a fulcrum so that the die will tilt and be permitted to expand after the thread has been cut and the operator wishes to release the die so that it may be removed from the cut thread.

The die comprises a fixed section 7 and an expanding section 8 carried by the usual parts 9. Interposed between the sections 7 and 8 are expansion springs 10 surrounding pins connected to one of said sections. The section 8 has a rounded outer edge 11 which is adapted to enter the supplemental cavity 2' when the die is tilted and which wipes under the top of the cavity 2 and contracts the die into cutting condition when the die is in normal position. The parts of the die are held in place by rings 12, 13, secured to said parts 9 by the screws 14 and there is the usual ring 15 which fits in the opening in the integral wall 3. The expandable section 8 has a cavity 16 or slot 16 which receives a pin 17 carried by 100

the ring or plate 13 for the purpose of limiting the extent to which the springs 10 may expand the die section 8. The ring 13 is provided with a bevelled notch 18 in the region 5 of the bevelled or rounded part 11.

There is a latch handle 19 which is connected at 20 to the stock 1 and may be held down by a bail or keeper 20 pivoted to a handle of the stock. Secured at 21 to the latch handle 10 19 is a latch 22 which has a bevelled end 23.

The latch 22 is adapted to be entered into the supplemental cavity 2' when the handle 19 is depressed, thereby to engage the rounded or bevelled part 11 of the die section 8. 15 and to enter the notch 18 for the purpose of holding the die in its normal screw threading position. If the keeper 20 is engaged with the handle 19, the die will be retained in normal position in the cavity 2 and can be 20 used for screw threading purposes.

If, however, the handle 19 be released from the keeper 20 and the die stock tilted on the work, the pin 6 will act as a fulcrum and the springs 10 will cause the die section 8 to expand 25 into the cavity 2'. The cavity 2' is provided with a bevelled wall 24 to facilitate this operation and also the operation of restoring the die to normal position.

The normal position of the die appears in 30 Fig. 2 and the released or expanded condition in Fig. 3. In each instance, a threaded bolt 25 is shown to illustrate the position of the parts during a screw threading operation and the position thereof after the thread 35 has been cut and the die has expanded to disengage its teeth from the bolt and to enable the die and the stock to be quickly removed from the bolt because the teeth of the die are clear of the screw threads on the bolt.

40 What I claim is:

1. In a releasing threading die, the combination with a die stock having a chamber for containing the die, of an expansible threading die located within said chamber and held in 45 contracted, screw-threading condition by the walls of the chamber, said chamber being of a width permitting the die to bodily tilt therein and having a supplemental cavity or enlargement which permits the die to expand 50 when said die is tilted, thereby to permit the die to open.

2. In a releasing threading die, the combination with a die stock having a chamber for containing the die, of an expansible threading die located within said chamber and held in contracted, screw-threading condition by the walls of the chamber, said chamber being of a width permitting the die to bodily tilt therein and having a supplemental cavity or 55 enlargement which permits the die to expand when said die is tilted, thereby to permit the die to open, and manually operable means for bodily shifting the die from expanded position into the chamber to effect contraction of 60 the die and to maintain it in contracted posi-

tion, said manually operable means, when released from the die, permitting the die to bodily tilt in the chamber and to project into the supplemental cavity so that the die may expand.

3. In a releasing threading die, the combination with a die stock having a cavity and provided with a fulcrum, of a threading die having relatively expansible parts and spring means for relatively expanding said parts when freed, a movable part of the die being provided with a cam surface, said die being adapted to assume a normal contracted position in the cavity or a tilted expanded position therein, said fulcrum serving to tilt the die when the die is released, and a latch adapted for manipulation at will, which co-operates with the cam surface of the die for the purpose of forcing the die into threading position, said latch then locking the die in that position.

In testimony whereof I affix my signature.
THOMAS COTTER.
